UNITED STATES PATENT OFFICE.

ALONZO LINTON BAUSMAN, OF SPRINGFIELD, MASSACHUSETTS, ASSIGNOR TO NATIONAL EQUIPMENT COMPANY, OF SPRINGFIELD, MASSACHUSETTS, A CORPORATION OF MASSACHUSETTS.

CONFECTIONERY-COATING MACHINE.

Application filed June 23, 1925. Serial No. 39,140.

This invention relates to improvements in confectionery coating machines and particularly to machines wherein the chocolate, or other coating, is applied in a liquid state to the goods and the latter are then passed from one conveying means to another while the coatings are still soft.

In machines of this type, there is a tendency for the plastic coatings to be drawn out or pulled away from the bases of the confections as they pass from one conveying means to another. This results in the formation of tails, so called, which, it is desired to eliminate. One way of eliminating these tails is by the use of a roll of small diameter which rotates in the space between the two conveying means and wipes off the trailing tails shortly after they are formed. Examples of machines having provisions for removing tails in this manner will be found in U. S. Letters Patent No. 1,302,205 granted April 29, 1919, on an invention of Antonio Pagliuca and No. 1,341,253, granted May 25, 1920 on an invention of Alonzo Linton Bausman.

The present invention is an improvement in tail removing devices of the class set forth and consists in rotating the tail removing roll in a reverse direction to that shown in the above identified patents. The upper peripheral portion of the roll, which portion functions to remove the tails, is therefore made to move in a direction opposite to that of the two conveying means between which it is located.

The result is that the tails, removed by the roll, are carried away from the plaque carrying delivery belt and toward the wire belt and are returned into the warm casing of the confection coating machine in a different manner than, but for the same general purpose as is set forth in the above mentioned Bausman patent.

Another and even more important result is that the described arrangement insures that the confection carrying surface of the delivery conveyer is kept clean, at least to the extent that any tails, which may be thrown outwardly from the tail removing roll due to centrifugal force, cannot lodge on the smooth confection carrying surface of the delivery conveyer.

Other features and advantages will ap-

pear in the following description and will be pointed out in the appended claims.

The invention will be disclosed with reference to the accompanying drawings, in which:

Fig. 1 is a fragmentary plan view showing the delivery portion of a well known type of confection coating machine and the adjacent and receiving end of the delivery conveyer;

Fig. 2 is a side elevational view of the parts shown in Fig. 1;

Fig. 3 is a sectional plan view taken on the line 3—3 of Fig. 2; and

Fig. 4 is an enlarged sectional elevational view taken on the line 4—4 of Fig. 1.

Referring to these drawings: A represents the two laterally spaced, upstanding side frames of the outwardly extending delivery end of a confection coating machine, such as that conventionally shown in the above mentioned Bausman patent. The confection coating machine may, of course, be of any suitable type and a full disclosure of one suitable type will be found in U. S. Letters Patent No. 735,890, granted August 11, 1903, on an invention of E. P. F. Magniez. The lower edges of the frames A are connected by a pair of spaced plates 6, the upper one of which is the equivalent of a drip pan to receive the chocolate dripping from the confection conveyer and return it into the main casing (not shown). The space between these plates forms a heating jacket. Mounted in the usual way for travel between frames A and above the uppermost plate 6 is the usual confection conveyer 7, which in its upper horizontal stretch of travel carries the freshly coated confections c and which is of wire mesh, or other suitable previous construction to allow the chocolate dripping from the confections to pass therethrough and fall upon the drip pan.

The coated confections, carried by the wire belt conveyer 7, are transferred when they reach the end of the upper stretch of travel of the wire belt, to a second or delivery conveyer 8, the confection carrying stretch of which is likewise horizontal and in the same or substantially the same plane as the corresponding stretch of wire belt 7. The receiving end of conveyor 8 is arranged as closely as feasible to the delivery

end of wire belt 7 and the confections, while their coatings are still soft and plastic, automatically pass from one conveying means to the other in the usual manner,—no special transferring means being required because the length of the gap between the two conveying means is so short with respect to the length of the bases of the confections *c*, as shown in Fig. 4. The conveyer 8 is provided with a smooth, impervious confection carrying surface 8', usually of waxed paper or the like, but instead of the single endless plaque formed by the part 8', a series of plaques may be used in the usual known manner and as shown for example, in U. S. Letters Patent No. 927,928, granted July 13, 1909, on an invention of Alonzo Linton Bausman.

The conveyers 7 and 8 may be driven in the usual, or any suitable manner. For example, these conveyers may be driven as shown in the above mentioned Pagliuca patent. In the drawings, a part of the usual gear train in the driving mechanism for wire belt 7 is shown at 9. A shaft 10, mounted in and extending between the side frames A, is driven at one end by train 9 and at its other end is connected by a chain 11 and suitable sprockets to drive the very small end roll 12 about which the wire belt turns in passing from its upper, confection-carrying stretch to its return stretch. The driving roll for wire belt 7 is indicated at 13 and is driven in the usual manner (not shown) by connections with shaft 10. The conveyers 7 and 8, in their upper and confection-carrying stretches, travel in the same direction as indicated by the arrows in Fig. 4.

The tail removing roll is shown at 15 and it is located in the gap between the adjacent ends of conveyers 7 and 8 and is disposed closely adjacent each. The relative location and proportions of the parts, usually used, is shown full size in Fig. 4, although of course, the size and spacing of the parts may be varied within considerable limits without departing from the teachings of the above mentioned Pagliuca patent. It is desired, for obvious reasons, to make the roll 15 as small in diameter as possible. As shown, the roll is smaller in diameter than the very small end roll 12 and, although smaller than shown in the illustrative disclosure of said Pagliuca patent, is approximately the same as is used in the practical and commercial embodiment of the Pagliuca invention. The roll 15, like that of the Pagliuca patent, is preferably located slightly below the plane of the confection carrying surfaces of the conveyers 7 and 8. However, there are means, in common use on confection coating machines, whereby the delivery conveyer can be raised or lowered to adjust its confection carrying sur-

face so as to lie above or below or truly tangent to the upper periphery of the roll and whereby the proximity of the end of belt 8 to roll 15 can be varied to bring it closer to or further away from this roll. 70

Such adjusting means are shown in the drawings, particularly in Fig. 4. The conveyer 8 in its upper stretch travels over a table 16, secured to and extending between a pair of angle irons 17, and secured to each 75 of the latter is a bracket 18 through which a screw 19 is threaded. The lower ends of the screws rest on brackets *b* formed one on each side of frame A. Accordingly, the plane of the table 16 and thus the confection carrying stretch of conveyer 8, can be raised or lowered with respect to the upper peripheral portion of roll 15. The adjustment is usually such that said portion of the roll will run as closely as possible to 85 the bases of the confections so as to remove the tails, such as *t*, without in any way wiping off or marring the bottom coatings. At the forward end of table 16, and arranged one along each side edge thereof, are 90 slides 20 each of which is connected to the table by bolts 21 riding in slots 22 in the slides, whereby movement of the slides longitudinally of the table can be effected. Adjusting screws 23, one for each slide, are 95 mounted in posts 24, secured to table 16, and these screws are arranged to bear on the upturned ends of the slides for moving them, when bolts 21 are loosened. The slides carry a cross bar 25, fixed at its ends thereto, and this cross bar is rounded along one edge to 100 guide belt 8 as it turns from its lower stretch of travel into its confection stretch of travel. By moving slides 20, the proximity of belt 8 to roll 15 can be adjusted, 105 as desired.

The adjustment of the level of the upper stretch of conveyer 7 with respect to the upper peripheral portion of roll 15 is, in this instance, effected by raising or lowering 110 the roll itself. The roll 15 has bearings in a series of circular plugs 26, 27, 28 and 29. The plugs 26 and 27 are mounted one in each of a pair of spaced arms 30, being held thereto by keys 31 and 32, respectively. 115 A pulley 33, suitably fixed to roll 15, lies between the arms 30, which are connected together above the pulley by an integral bridge 34. The plug 27 also extends into one end of a bushing 35 and in the other end 120 of the latter the plug 28 is mounted, both plugs being connected by the described key 32 to turn with the bushing. The bushing 35 is mounted in one side frame A so that it can be turned therein. The plugs 27 and 125 28 serve as bearings for the end roll 12 of the wire belt,—this roll passing centrally through the plugs, while roll 15 is located eccentrically thereof. Similarly mounted in the other side frame A is a bushing 36 130

which is similar to bushing 35, except that it extends beyond both sides thereof. The plug 29 is similarly fixed in one end of this bushing and at the other end thereof is another plug 37 which functions as a bearing only for the roll 12. The roll 15, being eccentrically mounted relatively to the bushings 35 and 36, it follows that by turning the latter the roll 15 can be raised or lowered without changing the level of roll 12, or of the belt 7, which is supported thereon.

The inner ends of the bushings 35 and 36 each receive the hub of an arm 38, which is radially split to receive a cross bar 39. The latter spans the space between the two arms 38 and bears against roll 12 to stiffen the same and also scrape chocolate therefrom. The ends of this bar 39, which are received in the split arms 38, may be clamped thereto by bolts 38' which act to draw the split portions of the arms together and also to bind the hubs of the arms on bushings 35 and 36. When bolts 38' are tightened, the cross bar 39 and arms 38 tie the bushings 35 and 36 together and the arms 38, or the bar 39, or the bridge piece 34 of arms 30, may be used as a means for simultaneously turning the bushings 35 and 36 to effect the raising or lowering of roll 15. Ordinarily this adjustment, once made, is not disturbed. Accordingly, the bushings 35 and 36 are made to fit tightly enough in side frames A so that they readily remain in their adjusted positions but, if necessary or desired, set screws 35 may be applied in frames A, as indicated in Fig. 2 at 40, to hold the bushings against turning therein.

The roll 15 is driven by a belt 41 which connects the pulley 33 to a relatively large pulley 42. In front of the pulley is a pinion 43 and both are fixed to a common bushing 44 which is rotatably mounted on a stud 45. The latter is fixed in one end of an arm 46. This arm, near its other end, is mounted to turn on a shouldered down part of the hub of a bracket 48 in which is fixed a stud 47. The bracket 48 is suitably secured, as indicated, to one side frame A. This bracket is provided with an outwardly projecting lug 49 which underlies the last named end of arm 46 and receives a screw 50 which can be turned to bear against said end to turn arm 46, and the pulley 42 carried thereby, in such direction as to tension belt 41. The arm 46 is held in adjusted position by a screw 51 which extends through a slot 52 in the arm and is threaded into the adjacent side frame A, whereby the arm 46 may be clamped against said side frame. The stud 47 underlies shaft 10 and carries a pinion 53 which is driven by the gear train 9 in the same direction as shaft 10. The pinion 53 is fixed to a bushing 54 which is rotatable on stud 47 and fixed to this bushing is a large gear 55. The latter meshes with pinion 43

but drives the latter and the pulleys 42 and 33 in a direction opposite to that of shaft 10 and opposite to the direction of travel of conveyers 7 and 8.

The driving mechanism described is so designed as to very greatly increase the speed of roll 15 over the speed of the conveyers 7 and 8. As shown, the number of revolutions of roll 15 is over fifty times as great as that of roll 10, which is one of the supporting rolls for conveyer 7 and is designed to travel at substantially the same surface speed as conveyer 7. The surface speed of roll 15 is approximately seven times as great as that of conveyer 7. In practice the roll 15 travels at about 1000 revolutions per minute and it will therefore be appreciated that any particles of chocolate, which are engaged thereby, are almost immediately thrown outwardly by the action of centrifugal force. With the arrangement, whereby the roll 15 moves in the opposite direction than heretofore, these particles are thrown toward the wire belt in its nonconfection conveying stretch of travel between rolls 12 and 13, and are carried back into a warm portion of the machine, whereby the removed tails cannot pile up and clog. No scraper is necessary to clean roll 15, as will be appreciated. The tails removed by roll 15 are thus thrown in such a direction that they cannot readily lodge on the confection carrying surface 8' of the delivery conveyer.

While the size and speed of roll 15 are variable within wide limits and the tail removing operation is essentially the same as that of the Pagliuca patent irrespective of the size and speed of the roll, the direction of rotation of the roll is a difference of another character. It has been found that the tail removing operation can be accomplished satisfactorily by wiping them away from the confections rather than toward and in under them and, as a consequence, the roll, rotating in a reverse direction, performs the same work but has the distinct advantage that the tails removed are thrown into the heated casing and not against the delivery conveyer. This means a saving in the cleaning of the paper surface of the delivery conveyer for the latter must be kept clean for satisfactory results.

The invention has been disclosed herein for illustrative purposes but the scope of the invention is defined by the appended claims rather than by the foregoing description.

What I claim is:

1. The combination with the confection carrying conveyer of a coating machine and a delivery conveyer located forwardly thereof for the transfer of confections from the former to the latter while the coatings on the confections are still soft, of a roll located in the space between the adjacent ends of

said conveyers and movable at high speed to wipe off the tails of the coated confections formed in leaving the first named conveyer, and means for driving said roll in such direction that any coating removed thereby and thrown therefrom by centrifugal force will be thrown against the first named rather than the last named conveyer.

2. The combination with the confection carrying conveyer of a coating machine and the supporting roll at the delivery end of its confection carrying stretch, of a roll mounted closely adjacent thereto and in parallel relation therewith for wiping off the tails

formed on the confections as the same pass off of said stretch of the conveyer, a supporting frame on each side of said conveyer, a member turnably mounted in each frame, and bearings provided in each of said members to rotatably receive both of said rolls, the bearings for said end roll being concentric with the axis about which said members turn and the bearings for said wiping roll being located eccentrically thereto.

In testimony whereof I have affixed my signature.

ALONZO LINTON BAUSMAN.
